UNITED STATES PATENT OFFICE.

WILLIAM B. WALKER, OF BLACKWELL, OKLAHOMA.

HARNESS.

Application filed September 29, 1924. Serial No. 740,582.

To all whom it may concern:

Be it known that I, WILLIAM B. WALKER, a citizen of the United States, residing at Blackwell, in the county of Kay and State 5 of Oklahoma, have invented a new and useful Harness, of which the following is a specification.

This invention relates to a harness and more especially to means fixed relative to the 10 traces for supporting the same.

Heretofore it has been the practice to mount the traces in supports in which the traces are free to move back and forth. This has resulted in rapid wear of the 15 traces so that the stitches soon break through and allow the parts to rip.

It is an object of the present invention to overcome the disadvantages heretofore present by providing supports which are 20 fixed relative to the traces, thereby materially reducing wear upon the parts.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 25 within the scope of what is claimed without departing from the spirit of the invention.

In the accompanying drawings the preferred form of the invention has been shown.

35 In said drawings—

Figure 1 is a side elevation of a portion of a harness having the present improvements combined therewith.

Fig. 2 is a perspective view of a portion 40 of a trace and one of the supports attached thereto.

Fig. 3 is a perspective view of one of the hip straps with a trace support connected thereto.

45 Referring to the figures by characters of reference 1 designates a back strip or billet such as commonly employed and 2 designates a bellyband. Various means have heretofore been provided for attaching the trace 3 to the back strap and bellyband but as a general rule these attaching means have 50 allowed the trace to work back and forth so

that it has soon become worn. In the present instance there is provided a support 4 made up of a leather strip folded as at 5 55 so as to receive the trace 3 within the fold. The leather strip 4 is stitched transversely as at 5' so as to prevent the fold from opening and rivets 6 are extended through the folded portion of the support 4 and through 60 the trace, thus securely uniting the parts. The support 4, in turn, is riveted or otherwise fastened, as at 7, to a strap 8 having looped ends 9 carrying rings 10 and 11 respectively. The ring 10 is adapted to be 65 engaged by the bellyband 2 while the ring 11 is engaged by the back strap 1. Thus it will be seen that the trace will be properly supported by the back strap but will not be 70 free to move relative to its support 4.

The hip strap of the harness has been indicated at 12 and is connected in any suitable manner, as by means of a ring 13, to a strap 14 which is looped through the ring 75 and has its ends lapping and riveted to the sides of a sleeve 15. This sleeve is formed of a piece of leather folded as shown and having its longitudinal edge portions stitched together as at 16. A trace is adapted to extend through the looped piece 15 80 and as this piece fits tightly upon the trace it will be held practically fixed relative thereto.

Obviously the improvements consisting of the supports fixed to the traces can be attached to different kinds of harness other than the one illustrated in the drawing.

What is claimed is:—

In a harness the combination with a trace, of a support comprising a piece of material 90 folded around the trace and fixedly attached thereto, a strap secured on the support and having terminal loops, rings engaged by the respective loops, a back strap engaging one of the rings, and a bellyband 95 engaging the other ring.

In testimony that I claim the foregoing as my own, I have hereto affixed my signature in the presence of two witnesses.

WILLIAM B. WALKER.

Witnesses:

JOHN P. BONICAMP,
TRESSA BURGER.
